UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed December 2, 1921. Serial No. 519,333.

To all whom it may concern:

Be it known that I, FRED S. CARR, a citizen of the United States, and a resident of Newton, in the county of Middlesex and State of Massachusetts, have invented an Improvement in Separable Fasteners, of which the following description, in connection with the accompanying drawings, is a specification, like characters on the drawings representing like parts.

This invention pertains to improvements in separable fasteners. It is among the objects of the invention to provide a fastener wherein the disengagement of stud and socket may be readily effected.

In the drawings, which show a preferred form of one embodiment of my invention:—

Figure 1 is a front elevation of a fastener with the parts applied to their carrying mediums;

Fig. 2 is a section on the line 2—2 of Fig. 1, being partly in elevation;

Fig. 3 is a section on the line 3—3 of Fig. 2, being partly in elevation, showing the jaws in stud-engaging position;

Fig. 4 is a section on the same line as Fig. 3, being partly in elevation and showing the jaws in stud-disengaging position; and

Fig. 5, 6 and 7 are views of details hereinafter referred to.

Referring to the drawings and to the preferred form of my invention selected for illustrative purposes, I have shown a stud including a head 5, neck 6 and a screw portion 7, the stud, preferably as illustrated, carried by a non-flexible carrying part 8 which may be a part of an automobile body.

Cooperating with the stud, I have shown a socket preferably, as illustrated, carried by a flexible carrying medium 9 which may be an automobile curtain. The socket illustrated presents jaw means typified by the jaws 10, with a resilient portion 11 urging the jaw means into engagement with the neck 6 of the stud as viewed in Fig. 3, these parts housed in a socket casing and preferably, as illustrated, located on that side of the curtain 9 from which the stud enters. The casing may be of any suitable form, but preferably as herein shown includes a back plate presenting a peripheral wall 13 surrounding but spaced away from the spring 11, the front of the spring and jaw containing a casing provided by a disc 14 herein

shown as a flange projecting outwardly from a cylindrical casing part 15 passing through the curtain 9 and held, with its cooperating parts, to the curtain 9 by prongs projecting from the wall 13 and clenched within a securing ring 16 (Fig. 7).

The preferred form of fastener illustrated is of the kick-off type, presenting kick-off means typified by the spring 20 compressed between the inwardly projecting flanges 21 of the cylindrical part 15 and a kick-off plate 22 pushing against the head 5 of the stud and tending to separate the socket from the stud as soon as the jaws of the socket are disengaged from the neck of the stud. In the fastener illustrated, the stud and socket when engaged may be disengaged by an inward push on the releasing part 24 which projects through the kick-off plate 22 (see Figs. 5 and 6) terminating in jaw-separating wedge means typified by the inclined faces 23 projecting between the jaws 10 and 11 at opposite sides of the stud.

The spring and jaws may be centered in the casing by locating means, preferably taking the form of lugs 24', 24" struck inwardly from the back plate 12 and preferably located immediately outside of the points of engagement of the wedge parts 23.

Assuming the stud and socket to be engaged as viewed in Figs. 2 and 3, and assuming the part 24 to be pressed inwardly, the wedge portions 23 will press apart the jaws 10, 10, releasing them from beneath the head of the stud, and at the same time the spring 20 will press outwardly on the flange 21 carrying the socket outwardly until on release of the part 24 (Fig. 2), the jaws will not again engage the neck of the stud.

During this operation, it should be noted that the inward pressure on the part 24 does not interfere with the kick-off spring 20 and that there is therefore no counter-acting of the kick-off force. Thus the fastener illustrated combines that ease of operation inherent to a push as distinguished from a twist or pull, and at the same time admits of satisfactory kick-off operation.

When the socket is to be engaged with the stud, the latter should be entered in the stud-receiving aperture and a push on the socket, other than the part 24, will cause the jaws 10, 10 to be separated by the head 5 of the stud until they snap into engagement with the neck of the stud, thus resum-

ing the relative positions shown in Figs. 2 and 3.

While I have shown and described a preferred form of one embodiment of my invention, it will be understood that changes involving omission, substitution, alteration and reversal of parts, and even changes in the mode of operation, may be made without departing from the scope of my invention, 10 which is best defined in the following claims.

Claims:

1. A fastener comprising, in combination, a stud having a head and a neck, a socket having stud-engaging jaw means, axial push-operated means for disengaging said jaw means from said neck of said stud and kick-off means for moving said jaw means away from said neck pursuant to disengagement of said jaw means from said neck, said kick-off means actively interposed between said stud and a portion of said socket movable independently of said axial push-operated means.

2. A fastener presenting axially push-operated stud and socket disengaging means in combination with kick-off means on the socket, said kick-off means operating in a direction opposite to the direction of push on said disengaging means, said kick-off means operatively interposed between said stud and a portion of said socket movable independently of said axially push-operated disengaging means.

3. A fastener presenting a stud having a head and a neck in combination with a socket presenting a jaw resiliently to engage said neck, axial push-operated jaw moving means for disengaging said jaw from said neck, and kick-off means carried by said socket exterior to said push-operated means, said kick-off means operative to move said jaw out of line with said neck independently of any corresponding movement of said jaw-moving means.

4. A fastener comprising, in combination, a stud, and a socket presenting resilient stud-engaging jaw means and relatively movable parts, one operable by pressure axial of said stud to disengage said jaw means from said stud and the other operable by similar pressure to engage said jaw means with said stud.

5. A fastener comprising, in combination,

a stud, and a socket presenting stud-engaging jaw means and telescopically relatively movable parts, the first of said parts operable by pressure toward said stud to disengage said jaw means from said stud and the second of said parts operable by similar pressure to engage said jaw means with said stud and kick-off means carried by the socket and moving said second of said parts away from said stud while the pressure is maintained on the first of said parts.

6. A fastener comprising, in combination, a stud, and a socket presenting stud-engaging jaw means and relatively movable parts one within the other, the inner of said parts operable by pressure toward said stud to disengage said jaw means from said stud and the outer of said parts operable by similar pressure to engage said jaw means with said stud, and kick-off means carried by the socket and moving said outer of said parts away from said stud while pressure is maintained on said inner of said parts.

7. A fastener comprising, in combination, a stud, and a socket presenting stud-engaging jaw means and relatively movable parts one within the other, the inner of said parts presenting a wedge portion and a projecting push button operable by pressure toward said stud to disengage said jaw means from said stud and the outer of said parts operable by similar pressure to engage said jaw means with said stud, and kick-off means carried by the socket and moving said outer of said parts away from said stud while pressure is maintained on said inner of said parts.

8. A fastener comprising, in combination, a stud, and a socket presenting stud-engaging jaw means and presenting two relatively movable face portions, the outer surrounding the inner, the inner operable by pressure toward said stud to disengage said stud and socket, and the other operable by similar pressure to engage said stud and socket, and kick-off means presenting portions behind both said inner and outer face portions and exerting separating pressure between said stud and the outer of said face portions.

In testimony whereof, I have signed my name to this specification.

FRED S. CARR.
